UNITED STATES PATENT OFFICE

133,217

DESIGN FOR A REAR VISION MIRROR

Jerome E. Poncher and Harold Poncher,
Chicago, Ill.

Application January 3, 1942, Serial No. 105,010

Term of patent 14 years

To all whom it may concern:

Be it known that we, Jerome E. Poncher and Harold Poncher, citizens of the United States, residing at Chicago, in the county of Cook and State of Illinois have invented a new, original, and ornamental Design for a Rear Vision Mirror, of which the following is a specification, reference being had to the accompanying drawing, forming a part thereof.

Fig. 1 is a top view of a rear vision mirror embodying our new design.

Fig. 2 is a side elevational view of the design

shown in Fig. 1 with the mirror portion tilted to show a perspective view thereof.

Fig. 3 is a rear view of our new design with the mirror in the same relative position as shown in Fig. 1.

Fig. 4 is a front elevational view thereof to a reduced scale.

We claim:

The ornamental design for a rear vision mirror, substantially as shown.

JERRY E. PONCHER.
HAROLD PONCHER.
